[57] CLAIM

The ornamental design for a serving dish or similar article, substantially as shown and described.

DESCRIPTION

FIG. 1 is a side elevational view of a serving dish or similar article showing my new design;

FIG. 2 is a bottom plan view thereof;

FIG. 3 is an end elevational view thereof;

FIG. 4 is a top plan view thereof; and

FIG. 5 is a sectional view taken along line 5—5 of FIG. 4.

The surface facet decoration visible through the dish bottom has been omitted from FIG. 4 for convenience of illustration.
